UNITED STATES PATENT OFFICE.

JAMES H. MATTHEWS, OF PITTSBURGH, PENNSYLVANIA.

DIE HOLDER.

Application filed February 7, 1924. Serial No. 691,091.

To all whom it may concern:

Be it known that I, JAMES H. MATTHEWS, residing at Pittsburgh, in the county of Allegheny and State of Pennsylvania, a citizen of the United States, have invented or discovered certain new and useful Improvements in Die Holders, of which improvements the following is a specification.

My invention relates to improvements in die holders, particularly in die holders such as are shown in Letters Patent of the United States No. 1,214,662, granted February 6, 1917, on the application of Joseph Escher and John Nagy, to James H. Matthews & Company, as assignee.

A die holder embodying my present invention is illustrated in the accompanying drawings. Fig. I is a view in side elevation of the die holder equipped with a set of dies; Fig. II is a view in medial and longitudinal section, on the plane indicated by the line II-II, Fig. I; Fig. III is a view in end elevation; and Fig. IV is a view in cross-section, on the plane indicated at IV-IV, Fig. I.

The body 1 of the die holder is provided terminally with a seat 2 in which an assembly of dies *d* may be placed. The seated dies are held in position by a lock 3, which, as clearly shown in Fig. II, passing through an opening in the holder enters notches formed in the bodies of the dies themselves to receive it. My invention concerns particularly the locking member 3.

As hitherto constructed, and as shown and described in the Escher and Nagy patent alluded to above, this locking member is essentially a metal strap anchored at one end in the body of the holder, and turned at the other end to form a right-angled tooth, to enter the notch in the die. A spring-backed bolt is employed to hold the metal strap in place with its toothed end in die-engaging position, and when shifted by manual pressure to flex the strap and allow the insertion and removal of dies to and from the holder. This locking member has been found to be the weak element in the holder. It soon breaks, and this breakage is a matter of considerable annoyance to the user, and therefore to the manufacturer as well.

After study and experimentation I have discovered how by modification in its form and mode of operation I can improve this locking-member and cause it to endure long and satisfactory service. I make it no

longer as a strap anchored at one end, but as a plate mounted to move without flexure and I modify it in shape, so that it is not bent abruptly at a right angle to afford a terminal die-engaging tooth.

As shown in the drawings the locking member 3 is formed of a strap or plate of steel secured to and borne by, and borne solely by the bolt 5. The bolt 5 extends through and beyond a transverse opening formed in the body of the holder, and within this opening it is encircled by and engaged by a spring 6 of sufficient power to hold it normally (as seen in Fig. II) at the right-hand end of its range of movement and to hold the locking member which it carries, in die-engaging position.

The die-engaging end 4 of the locking member 3 is not a mere tooth turned aside at the tip of the long locking member, it is the terminus of a long crook 7 formed by bending into a compound curve the end of the strap of which the locking member is formed. The particular shape which I have found efficacious and satisfactory is fully illustrated in Fig. II.

In three respects particularly I have improved upon the locking member of the prior art, and produced a more serviceable article. First, I have eliminated from the locking member itself flexure in operation. Second, I have separated the locking member from immediate anchorage upon the body of the die holder; it is carried meditately, by bolts 5 and spring 6. Third, I have introduced the long crooked neck leading to the die-engaging tip 4.

The prior-art structure, I have discovered, breaks in consequence of a crystallization of its constituent metal. And by the changes in shape and mounting and in mode of operation, which now I have described and indicated, I have so far eradicated the tendency to crystallization, that I have a die holder which in all its parts is durable, beyond what hitherto has been produced, and satisfactory in that respect, where the prior-art structure is annoying and unsatisfactory.

I claim as my invention:

1. A holder for a removable die consisting of a body member provided with a die-seat, a spring-backed bolt extending transversely through and movable within an opening in said body member, and a locking member borne by said bolt alone and

movable with said bolt to and from die-engaging position.

2. A holder for a removable die consisting of a body member provided with a die-seat, a spring-backed bolt extending transversely through and movable within an opening in said body member, and a locking member in the form of a strap engaged by said bolt and at its free end shaped to a crook

of compound curvature terminating in a 10 die-engaging tip.

In testimony whereof I have hereunto set my hand.

JAMES H. MATTHEWS.
